Coleman H. Feldman, Los Angeles, Calif.

Application November 10, 1952, Serial No. 22,221

Term of patent 14 years

(Cl. D15—1)

To all whom it may concern:

Be it known that I, Coleman H. Feldman, a citizen of the United States, residing at Los Angeles, in the county of Los Angeles, State of California, have invented a new, original, and ornamental Design for a Combined Seat and Backrest Cushion, of which the following is a specification, reference being had to the accompanying drawing, forming a part hereof.

Figure 1 is a front perspective view of a combined seat and backrest cushion embodying my new design;

Fig. 2 is a top plan view of the same;

Fig. 3 is a rear perspective view of the same; and

Fig. 4 is a vertical section taken substantially upon the line 4—4 of Fig. 1 in the direction indicated.

I claim:

The ornamental design for a combined seat and backrest cushion, as shown.

COLEMAN H. FELDMAN.
